United States Patent Office

Des. 201,059
Patented May 4, 1965

201,059

PROJECTION READER

Ralph M. Vigna and Kenneth Wayne Scott, Rochester,
N.Y., assignors to Eastman Kodak Company, Rochester,
N.Y., a corporation of New Jersey

Filed Aug. 7, 1964, Ser. No. 81,202

Term of patent 14 years

(Cl. D61—1)

FIG. 1

FIG. 2

FIGURE 1 is a front perspective view of a projection reader showing our new design; and

FIGURE 2 is a front perspective view showing the other side thereof.

The rear and bottom of the projection reader are plain and unornamented.

We claim:

The ornamental design for a projection reader, as shown and described.
